UNITED STATES PATENT OFFICE.

CHARLES T. SCHNEIDER, OF MILWAUKEE, WISCONSIN, ASSIGNOR OF ONE-HALF TO
THOMAS SIDERITS, OF MILWAUKEE, WISCONSIN; LOUISE SCHNEIDER ADMINIS-
TRATRIX OF SAID CHARLES T. SCHNEIDER, DECEASED.

DOOR HANGER.

Application filed July 13, 1925. Serial No. 43,251.

This invention relates to door hangers.

In door hangers, as previously constructed, it has been found difficult to detach the door from the hangers, and further than this, due to the relatively rigid connection between the hanger and the door, it has been impossible to secure an equal bearing for the supporting rollers of each of the trucks where a plurality of rollers are used in a truck.

This invention is designed to overcome the above noted defects, and objects of such invention are to provide a door hanger in which a truck equipped with a plurality of rollers is employed, in which the truck is pivotally attached to the door and independently adjusts itself to the guide, and in which a very quick and easily detaching of the door from the hangers may be secured.

20 An embodiment of the invention is shown in the accompanying drawings, in which:—

Figure 1 is a view of the hanger attached to a door with a part of the hanger in section.

25 Figure 2 is a vertical sectional view through the hanger.

Figure 3 is a section on the line 3—3 of Figure 1.

Referring to the drawings, it will be seen that the door is indicated at 1 and the usual guide at 2. The hanger comprises a truck consisting of an outer plate 3 which has an inturned bottom portion 4 provided with an upturned lip 5, such upturned lip forming a channel-like member with the hanger. The upper portion of the hanger is provided with a pair of outer spacing members 6 and with an intermediate member 7 which are integrally joined to the main plate 3 and to 40 an inner plate 7', such inner plate being held in spaced relation to the main plate, as most clearly shown in Figure 2.

A pair of rollers 8 are carried by bearing pins 9 which are riveted or otherwise secured to the plates 3 and 7, as shown in Figure 2. If desired, ball bearings may be provided for the rollers to reduce friction. A top or cover portion 10 is also provided which is curved to correspond to the upper portion of the rollers. This cap may be formed integrally with the members 3 and 7, if desired, but preferably it is detachably secured in place by means of a screw 11 passing therethrough

and threaded into the central spacing member 7.

55 In this connection, it is to be noted further that the spacing members 6—6 and 7 reinforce the device and insure an extremely rigid construction.

A small roller 12 is positioned between 60 the members 3 and 5 and is preferably off center, as shown in Figure 1.

A pintle pin 13 is secured to the members 3 and 5 centrally of the lower position of the truck. This pintle pin receives the eyeleted portion 14 of a bolt 15. The lower end of the bolt is screwed into a foot piece or clip 16 and preferably a nut 17 is provided for rigidly locking the bolt in place. The clip 16 is provided with short arcuate 70 slots 18 at opposite ends which opens through opposite sides. These slots are adapted to receive the shanks of the bolts 19, such bolts being secured to the door 1.

In attaching the device, the door is suitably positioned and the clip 16 is swung in a clockwise direction from its dotted line position, shown in Figure 3. Thereafter, the bolts or screws 19 are tightened against the 75 clip, thus locking the clip rigidly to the door. The lock nut 17 is then screwed down against the clip 16.

It is obvious that the exact spacing of the door from the guide 2 may be secured by detaching the clip from the door and adjusting it upon the bolt 15.

It will be seen that due to the pivotal connection of the bolt and truck that the equal distribution of weight between the rollers 8 will be assured, and an easy and 90 free riding truck is secured. It is also to be noted that the peculiar construction of clip 16 insures an accurate adjustment of the door with reference to the slide, and also a quick easy assembly of the device, thus facilitating repairs.

Although the invention has been described in considerable detail, it is to be understood that the invention may be variously embodied and is, therefore, to be limited only 100 as claimed.

I claim:

A door hanger comprising a truck having a main plate extending from its upper portion to its lower portion and having an upper and lower auxiliary plate spaced from

2
and integrally joined to said main plate, a pair of supporting rollers carried between said main plate and the upper auxiliary plate, a third roller carried between the lower auxiliary plate and the main plate, a threaded pin pivotally mounted between said auxiliary lower plate and the main plate, said pin having its point of pivotal connection with said truck located adjacent the lowest portion of said truck, the axis of the

pivot extending transversely of said truck, and means adjustably carried by said threaded pin for detachably engaging the door.

In testimony that I claim the foregoing I 15 have hereunto set my hand at Milwaukee, in the county of Milwaukee and State of Wisconsin.

CHARLES T. SCHNEIDER.
